(57) **CLAIM**

The ornamental design for a vehicle taillight, as shown and described.

DESCRIPTION

FIG. 1 is a first perspective view of a left vehicle taillight, as seen from the rear of a vehicle (the right vehicle taillight being a mirror of the left and is not illustrated);

FIG. 2 is a second perspective view of the vehicle taillight;

FIG. 3 is a front elevational view of the vehicle taillight;

FIG. 4 is a left side elevational view of the vehicle taillight;

FIG. 5 is a right side elevational view of the vehicle taillight;

FIG. 6 is top plan view of the vehicle taillight;

FIG. 7 is a bottom plan view of the vehicle taillight; and,

FIG. 8 is a rear elevational view of the vehicle taillight.

The vehicle taillight is styled independently of adjacent vehicle panels. To the extent that any feature lines are illustrated, they are intended to illustrate the crest and valley of the feature and are not necessarily sharp bends in the part. Shading is used to illustrate the curvature of the part and not color. Views are orthogonal projections. The various views are not necessarily to scale in order to better illustrate the design.
